CLAIM

The ornamental design for a finger gadget, as shown and described.

DESCRIPTION

FIG. 1 is a perspective view of a finger gadget showing my new design;

FIG. 2 is a front elevation view thereof, the rear elevation view being an identical image thereof;

FIG. 3 is a left side elevation view thereof, the right side elevation being an identical image thereof;

FIG. 4 is a top plan view thereof, the bottom plan view being an identical image thereof; and,

FIG. 5 is a perspective view of the finger gadget in use. The broken lines showing the human hand form no part of the claimed design, but are included for the purpose of illustrating the design in its intended environment.

1 Claim, 3 Drawing Sheets
